CHECK DISPLAY MECHANISM

Hugo J. Baur and Thomas E. Kulo, Chicago, Ill., assignors, by mesne assignments, to City National Bank and Trust Company of Chicago, Chicago, Ill., as trustee

Application February 17, 1941, Serial No. 379,379

9 Claims. (Cl. 194—98)

This invention relates to a mechanism for displaying checks which are mechanically collected so that they may be visually inspected, for passing said checks through a plurality of visible stations and for finally depositing them in a container.

The mechanism is intended for use with a fare register such as that disclosed in our application Serial Number 350,312, filed August 3, 1940, for "Fare registering mechanism."

It is an object of the invention to provide a plurality of check supporting elements which are disposed to successively receive a check and to display it.

Another object of the invention is to provide a mechanism for dumping the checks from each of the supporting elements in predetermined sequence.

A further object of the invention is to provide means for releasing said checks from the check receptacle so that they may be used again.

Yet another object of the invention is to provide a check dumping mechanism in which the last or lowermost check supporting element is first actuated through a cycle and thereafter other elements are actuated seriatim.

It is still another object of the invention to provide a check feeding and display mechanism which serves to feed the checks toward the last check supporting element and which clears the first element for the reception of a newly registered check.

Another object of the invention is to provide check supporting means which may be manually cleared of all except the last registered check.

These and other objects will become apparent from a study of this specification and the drawings which form a part hereof, and in which:

Figure 1 is an elevation of the check receiving mechanism and the display element operating mechanism.

Figure 2 is a front elevation, with parts broken away, of the display mechanism and its associated actuating linkage.

Figure 3 is a sectional view taken on the line 3—3 of Figure 2 showing the check supporting elements, the check receptacle and the actuating mechanism.

Figure 4 is a sectional view taken on the line 4—4 of Figure 2 showing the operator for the last check support.

Figure 5 is a sectional view on the line 5—5 of Figure 2 showing the operator for the intermediate check supporting element.

Figure 6 is a view similar to Figure 1 but show-

ing the timing mechanism which connects the cam-shaft and the crank-shaft.

Figure 7 is a figure similar to Figure 6 but showing the relation of the parts at the end of the 5 check locking phase of the cycle with a minimum diameter check in place.

Figure 8 is a figure similar to Figures 6 and 7 but showing the relation of the parts at the beginning of the check releasing phase.

10 Figure 9 is a figure similar to Figures 6, 7 and 8 showing the relation of the parts at the time the check is ejected from the caliper mechanism.

Figure 10 is a top view with parts removed showing the structure of the check braking mechanism and its relation to the slide.

15 Figure 11 is an elevation of the check braking mechanism of Figure 10.

Figure 12 is an elevation showing the check stripper plate.

20 Figure 13 is a section taken on line 13—13 of Figure 12.

Figure 14 is a section taken on line 14—14 of Figure 1, showing the comb guide for the cam levers.

25 Referring to Figure 1, the numeral 1 represents a check receiving chute and 3 represents a check support or receiver which is connected to be reciprocated by a slide 5. The slide is reciprocated by a rack 7 which is in engagement 30 with a sector 9 and is driven by the linkage indicated generally by the letter A.

The linkage is actuated by a crank 11 which is mounted on a crank-shaft 15. The shaft 15 carries a gear 8 (Figures 8 and 9) fixed to it and 35 a locking sector 10 which occupies a fixed relation with respect to the crank 11 and is disposed with the gear between it and the crank.

The slide 5 is provided with a shoulder 5' which has less depth than the thinnest check to be 40 used. As the slide is moved to the left in Figures 1 and 6 to 9, a check resting in the support 3 resting on 19 will be contacted by the shoulder 5', forced from under the stripper 12 (Figures 8, 9 and 13) and moved into engagement with the 45 anvil 13 where it is held. The contacts 19 are mounted in a block of insulation which is fixed to, and moves with the slide 5 and rack 7, which are supported in guide means mounted on frame member 77. The anvil 13 is adjustably supported on the frame member 22 which is in turn supported on frame member 77.

The stripper plate 12 (Figures 12 and 13) is provided with a pair of bent over ears 44 which are perforated to receive a pivot pin 12' which 50 is supported in ears on the frame member 52.

A spring 44 supported by pin 12 urges the stripper into contact with the slide. Projecting from the side of the plate in a direction opposite from that of ears 44 is a check stripping lip 46 which is cut away as shown at 48 and is bevelled as shown at 50. The check to be calipered engages the lip 46 and will be held while the inclined portion 3' (Figure 9) of the support 3 is moved under the check and raises it; and as the check is contacted by the shoulder 5', it will be forced under the bevelled edge 50 and thus the check will be stripped from a stack of checks which may have been deposited in the support 3.

A pin 42 is mounted in the plate 12 and extends in the same direction as lip 46. This pin 15 rests upon a frame member 52 so as to hold the edge 50 from contact with the slide 5. This reduces wear on the parts 5 and 50.

The crank-shaft 15 is driven by gear 8 which in turn is driven by gear 14 mounted on cam-shaft 17. Also mounted on 17 is a locking sector 16 which cooperates with sector 10. In the initial position, the shafts 15 and 17, the gears 8 and 14 and the sectors 10 and 16 occupy the relations shown in Figure 6. That is, the crank is on dead center with respect to its associated link; the cut away portion of sector 10 is a half revolution away from its locking position and the gear 14 and sector 16 are bisected by the line joining the centers of the shafts 15 and 17. The cams 92, 94 and 96 are 120 degrees apart and cam 94 is also bisected by the same line of centers just referred to.

The number of teeth on the gears 14 and 8 is such that sixty degrees of rotation of the gear 14 will rotate gear 8 and the crank 11 180 degrees and position the locking sector 10 for engagement with the sector 16. This position of the parts is shown in Figure 7.

As is clearly shown in this figure the check C 40 has been gripped between the shoulder 5' and the anvil 13 as described above and is thus in the position in which it is calipered.

Pivotedly mounted on a stud 20 (Figures 6 to 11) which is fixed to a frame member 22, is a lever 24 having an upstanding ear 26 (Figures 10 and 11). The lever carries a screw 28 which holds a clutch element 30 in fixed position on the lever. This element is provided with a V-shaped notch 32 in which is freely mounted a clutch roll 34. A knurled wheel 36 encloses the element 30 and a washer 38 overlies the wheel and holds the various parts in their respective positions.

A spring 40 bears against the ear 26 at one end and against a frame member not shown at its other end and thus serves to urge the lever 24 in a clockwise direction (Figure 10) to press a check C against the slide 5.

The roll operating in the notch 32 is adapted to engage the inner periphery of the knurled wheel 36 and to prevent counter clockwise rotation thereof (Figure 10) while permitting free rotation in a clockwise direction.

The shafts 15 and 17 are driven by a motor, not shown, through three hundred sixty degrees every time a check is deposited upon the motor control contacts 19 mounted in the check support 3. This mechanism, too, is fully described in the above mentioned application.

Surrounding the slide and anvil is a check hopper 21 (Figure 1) which has a slanting bottom 23 which leads to an opening 25. A lip 27 on the hopper projects into the display casing 29 which is open at its upper end to receive checks which are discharged from said chute.

The casing comprises a vertical trough 31 which is fixed to a front member 33 which is preferably a cast frame. This frame is provided with a sight opening 35 (Figures 2 and 3) and is fitted with a window 37 in any suitable manner.

A plurality of horizontal shafts 39, 41 and 43 are mounted transversely in the trough 31 and a plurality of check supporting elements or shelves 45, 47 and 49 which are provided with upwardly bent and perforated ears 51-57, 53-59 and 55-61 respectively are supported for rotation upon said shafts.

Coiled springs 63, 65 and 67 are mounted on said shafts and tend to hold the shelves in the check supporting position with their left-hand edges (Figure 3) against the glass 37 so as to close the trough against the passage of checks.

Pins 69, 71 and 73 project laterally from the ears 57, 59 and 61 through slots in the one wall of trough 31.

As is clearly shown in Figure 1, a bracket 75, which is fixed to a frame member 77, supports a pivot pin 79 upon which are pivotally mounted in spaced parallel relation three levers 81, 83 and 85 having cam followers 87, 88 and 90 respectively formed on their intermediate sections. The levers 81, 83 and 85 are guided in a comb guide 89 which is also fixed to the frame member 77.

Three separate cam plates are mounted in parallel relation on the shaft 17 and are fixed thereto. Each plate carries a cam and the cams designated by numerals 92, 94 and 96, respectively, are spaced 120 degrees apart, circumferentially.

A link 91, Figures 1 and 3, connects the pin 69 of the shelf 45 with a pin 93 in the outermost lever 81. A bent link 95, Figure 5, connects the pin 71 with a pin 84 on the intermediate lever 83 so that the intermediate shelf 47 will be actuated thereby. The innermost lever 85 connects directly with the pin 73 on the lowermost shelf 49.

In addition, a link 97 having slots 99 and 101 therein, Figure 4, is adapted to fit over the pins 71 and 73 and is connected at its lower end to a link 103 by means of a pivot pin 105. The link 103 is provided with a stub shaft 107 on which is mounted a roll 109. The roll is adapted to ride on the edge 111 of the front member 33 as is clearly shown in Figure 1.

The lower end of link 103 is pivotally connected at 104 with a projecting ear 106 of a tilting plate 113 which is pivotally mounted on a shaft 115 and which serves as a bottom for the check receptacle 117. The plate projects from under the front member 33 and is formed with turned up edge portions 119 and serves as a chute for the checks leaving the receptacle.

The plate 113 carries a U-shaped bail 121 having depending end portions 123 between which is mounted a shaft 124 which, in turn, carries cam rolls 125. One longitudinal edge of the central portion of the bail is bent downwardly to form a stop 127 for the actuating plate 129 which is pivotally mounted on the transverse shaft 131 by means of the depending supports 133.

The plate 129 is provided with slots 135 at either side which receive the end portions 123 of the bail 121 and with a transverse opening 137 which provides clearance for the stop 127.

The supports 133 are formed with roll actuating cams 139 which are adapted to engage the roll 125. A spring 141 mounted on shaft 131 engages the bottom of the member 33 and the plate 129 at its upper end, and serves to hold it in its

farthest counter clockwise position which is with its upper edge in engagement with stop 127.

Operation

When a check is deposited in chute 1 it will descend and come to rest upon contacts 49 and start the motor (not shown). The motor will drive the cam-shaft 17 and during the first 60 degrees of its revolution, the gear 14 will rotate the gear 8, sector 10 and crank 11 through a half revolution and will, through linkage A, sector 9, rack 7, slide 5 and support 3 grip the check between the anvil 13 and shoulder 5' to caliper it. Thereafter, the cam-shaft 17 is rotated through two hundred forty degrees in a clockwise direction. During the first 60 degrees movement, from the Figure 6 to the Figure 7 position, of the cam-shaft, the cam 96 will actuate the cam follower 80 and lever 85 to pull the pin 13 downward so as to tilt the lowermost shelf 49 and dump the check supported thereby into the check receptacle 117. Upon further rotation of the shaft, cam 96 will release the lever 85 so that the shelf may be restored to its check supporting position by the spring 67. This operation will be completed within the first 120 degrees rotation of shaft 17.

During the next sixty degrees of movement, the cam 94 actuates follower 88 on lever 83 which pivots and pulls downward on link 95 and pin 71 (Figure 5) to tilt the intermediate shelf 47 so that the check therein will fall to the lowest shelf 49 and will be retained for inspection thereon.

The shelf 47 will be returned to its initial check supporting position by spring 65 when the cam 64 releases its follower 90. This event occurs well before the completion of the second one hundred twenty degree rotation since each cam has a face width of sixty degrees. There will accordingly be rotation of slightly less than 30 degrees at the beginning and end of each 120 degree phase during which the cam follower occupies its rest position. The rise and fall portions of the cams utilize only a few degrees of the travel.

It will be noted that the slots 99 and 101 in link 97 (Figure 4) permit the movement of the pins 71 and 73 and their associated shelves as just described without the link being moved.

During the third one hundred twenty degrees of revolution of shaft 17, the cam 92 will actuate the follower 87 as shown in Figure 8 and the outer lever 84 will pivot and pull down on link 91 and pin 69 to dump shelf 45 causing the check which is supported thereon to be deposited on the shelf 47. The shelf 45 will be restored by spring 63 to the initial position as the cam passes its follower and moves to its initial position.

As the cam-shaft 17 enters upon the last sixty degrees of its rotation, the locking sector 16 moves out of engagement with sector 10 and gear 14 engages gear 8 so as to transmit rotation thereto to return it to its initial position.

As the crank 11 is thus rotated the shoulder 5' backs away from the caliperized check which is now held between the spring pressed roll 36 and the surface of the slide 5. The check is prevented from returning with the slide by the friction between it and the knurled roll. Since the roll is prevented from rotating in the counterclockwise direction (Figure 10) by the clutch 32-34, the slide will move relative to the check and the roll until the left end of the slide clears or nearly clears the check as is shown in Figure 9, whereupon it will be pushed by the roll and will fall

down into the hopper 21. It will roll or slide down the inclined bottom thereof into the trough 31 where it comes to rest on the uppermost shelf 45 where it can thus be viewed by any interested person.

From Figure 9 it will be noted that at the time of release of the check of smallest diameter, the cam 92 has already cleared its follower 87 so that the upper shelf 45 will have been positioned by its spring to receive the check before the check is released.

Obviously, if a larger check is used than that shown, the release thereof will be even later with respect to the release of the cam follower 92. The same result follows if the check should be carried back with the slide 5 due to the failure of clutch 32, 34 to function. It will eventually rest against stripper 42 and the slide will be withdrawn from in front of it (see Figure 6). In either event the shelf 45 will be in position before the check is released.

It will be seen that this cycle is repeated for every check deposited and that where a fare consists of several checks such as a nickel and two pennies, the entire fare will be displayed on the shelves in the order individual checks were registered.

To remove checks from the receptacle 117, lifting pressure is applied to the outer end of plate 129, preferably with the thumb of the cupped hand. Such pressure produces a clockwise rotation of the plate 129 about shaft 131 and as a result the outer ends of the cams 139 will engage the rolls 125 and induce a counterclockwise rotation of plate 113 with the result that the checks in the receptacle will slide down the plate 113 and into the cupped hand of the operator. The plates 113 and 129 in the fully actuated position occupy contiguous and parallel positions so that the stop 127 occupies the clearance slot 137.

The operation of plate 113 by plate 129 also transmits a downward pull on the links 103 and 97. The roll 109 bearing on the edge 111 prevents the link 103 from pivoting about 105.

It will be seen from Figure 4 that the pins 71 and 73 lie in the upper ends of slots 99 and 101 respectively so that these pins will be pulled downwardly by the link and will tilt the lower and intermediate shelves 49 and 47 simultaneously to dump the checks held by them into the receptacle 117 whence they will be deposited in the operator's hand. The levers 85 and 83, connected to these pins, will simply pivot idly about the pivot 79. Thus it will be seen that all but the last check collected will be delivered to the operator.

While the preferred form of the apparatus has been disclosed herein for the purpose of illustration, it is obvious that various changes may be made in the form, construction and arrangement of parts without departing from the spirit of the invention. Applicants therefore do not wish to be limited to the specific construction disclosed but desire protection falling fairly within the scope of the following claims.

What we consider to be new and desire to protect by United States Letters Patent is:

1. In a check display apparatus, the combination of an actuating means, check handling means including movable means connected to said actuating means and operable thereby to engage and move a check to a predetermined position, hold and thereafter release said check, a plurality of check supporting elements, the first 75 of which is disposed adjacent said predetermined

position so as to receive said check from said check handling means when the check is released and the remainder of said elements being disposed to receive the check in turn, means cooperating with said elements to retain a check supported thereon, means operable by said actuating means to move said elements from and to check retaining position in predetermined order to pass a check from one element to the next, said operable means being adapted to complete the movement of one element before actuating another, said actuating means being constructed and arranged to move said movable means to release the check engaged therewith after the movement of said first element is completed.

2. In a check display apparatus, the combination of a plurality of check supporting elements, means mounting said elements for movement from and to check supporting positions and means for moving said elements individually and in predetermined order and additional manual means for moving all but the last moved check supporting element from check supporting position.

3. In a check display mechanism comprising a transparent element, a check handling mechanism, means operated continuously throughout a cycle for actuating said mechanism to move a check to a predetermined position, to hold and thereafter to eject said check, a check receptacle, a series of display elements disposed adjacent said predetermined position, said receptacle and said transparent element, cam means operated by said actuating means for actuating said display elements in sequence, from the lowermost to the uppermost, to pass checks received from the check handling means, by stages past said transparent element to said receptacle before said check handling mechanism is actuated to eject a check to the display element adjacent to it.

4. In a check display apparatus a display casing, a plurality of check supporting elements superposed one above the other in said casing, means mounting said elements for movement from and to check supporting position, yieldable means normally retaining said elements in check supporting position, and means for actuating said elements from check supporting position in order from the lowest to the uppermost and additional means operable at will for moving all but said uppermost element from check supporting position.

5. In a check receiving and display mechanism, a display case, a plurality of check supporting elements mounted in said case for movement from and to said check supporting position and arranged to pass a check from one element to the next succeeding element, check handling means including means for ejecting a check therefrom, actuating means for moving said elements from and to check supporting position in sequence from the first to the last, to pass said checks from one element to the next, means connecting said actuating means and said ejecting means to effect actuation of the latter after said supporting elements have been actuated, and means for guiding said ejected check from said check ejecting means to the first of said supporting elements.

6. In a check display mechanism comprising

10 a transparent element, a check handling mechanism adapted to move a check to a predetermined position, hold and thereafter eject said check, a check receptacle, a series of display elements disposed adjacent said predetermined position and between said handling mechanism and said receptacle and adjacent said transparent element, means for actuating said display elements to pass checks by stages past said transparent element to said receptacle, and for thereafter actuating said handling mechanism to eject a check to the display element adjacent to it and manual means for releasing checks from said receptacle, said manual means being connected to actuate display elements to release checks held by them.

15 7. In a check display mechanism, the combination of a transparent element, a plurality of display elements disposed adjacent thereto, means for actuating said display elements to move a check by intermittent stages past said transparent element, a check handling mechanism comprising a check gripping and supporting slide adapted to move to supporting gripping position and return, means for actuating said check handling mechanism, a check friction wheel, means mounting said wheel for yieldable engagement with a slide supported check, said mounting means comprising a clutch adapted to prevent movement of said wheel as said slide moves from gripping position whereby a check will be held against movement with the slide in said return direction and will be ejected as said slide moves out of check supporting position, said actuating means being so coordinated in movement with the movement of the display elements as to complete operation of said display elements prior to the withdrawal of the slide from supporting position.

20 8. In a check handling mechanism, an anvil, means including a shouldered slide adapted to support and move a check, a friction wheel, means mounting said wheel for rotation in one direction about an axis, means for pressing said wheel toward said slide, means for moving said slide toward and from said anvil into and out of position adjacent said wheel, and a hopper disposed adjacent said wheel and anvil whereby a check will be moved to said anvil to be engaged and held by said wheel against return motion with said slide and will be discharged into said hopper when said slide is withdrawn.

25 9. In a check receiving and display mechanism, a display case, a plurality of check supporting elements mounted in said case for movement from and to said check supporting position and arranged to pass a check from one element to the next succeeding element, check handling means including means for clamping and thereafter ejecting a check therefrom, actuating means for moving said elements from and to check supporting position in sequence to pass said checks from one element to the next, means connecting said actuating means and said clamping and ejecting means to effect actuation of the latter after said supporting elements have been actuated.

HUGO J. BAUR.
THOMAS E. KULO.
